DESIGN FOR AN AUTOMOBILE GEAR SHIFT
KNOB OR SIMILAR ARTICLE

George Berkson, Chicago, Ill.

Application December 9, 1938, Serial No. 81,686

Term of patent 14 years

To all whom it may concern:

Be it known that I, George Berkson, a citizen of the United States, residing at Chicago, in the county of Cook and State of Illinois, have invented a new, original, and ornamental Design for an Automobile Gear Shift Knob or Similar Article, of which the following is a specification, reference being made to the accompanying drawing, forming a part thereof, in which—

Fig. 1 is a top plan view of an automobile gear

shift knob or similar article, embodying my new design; and

Fig. 2 is a side elevational view of the same.

The device of my design is also adapted to be used as a steering wheel control knob.

I claim:

The ornamental design for an automobile gear shift knob or similar article, as shown and described.

GEORGE BERKSON.
